Application October 21, 1936, Serial No. 106,892

3 Claims. (Cl. 210—199)

This invention relates to new and useful improvements in mud screens, for the purpose of separating solid materials from liquids.

In the drilling of oil wells and the like, it has recently become known that the condition maintained in the mud characteristics of the fluid used for removing the cuttings from the well-bore, and for conditioning the walls of said well-bore, is of great importance. In order to maintain these desired characteristics, it is necessary to remove from the drilling fluid, all particles of granulated formations that is possible. This is also necessary for the proper maintenance of the mud pumps and tubular equipment, through which the mud has to be handled from the pumps to the bit at the bottom of the well-bore.

One object of this invention is to afford an apparatus for the efficient separation of these granulated formations from the drilling fluid and wherein the reticulated sections of the screening assembly are held wedged in place without the use of bolts and nuts.

Another object of the invention is to afford equipment for this purpose that is self-governing in its speed of operation.

Another object of this invention is to afford an apparatus for this purpose, the power for operation of which is supplied largely by the mass and velocity of the fluid handled.

A further object of this invention is to afford equipment of sturdy construction, and having replaceable parts, which are easily and cheaply replaced.

With these and other objects in view, as will be obvious from the description to follow, I here set forth one and a preferred form of this invention, as shown in the drawing herewith attached, in which

Figure 1 shows a side elevation of the apparatus, and

Figure 2 shows an end elevation on the discharge end of the apparatus, and

Figure 3 shows a detailed construction of the screen sections, as fastened to the main body of the machine, and

Figure 4 shows a side elevation of one of said screen sections.

Referring more particularly to the drawing, in which similar numbers represent similar parts in all figures, the invention consists of the runners joined together by the cross-members 11. Supported on these cross-members by vertical members 12 and 13, are the cross-members 15, on which are stationed the journal boxes 14, in which is rotatably mounted the main shaft 18.

Mounted on the main shaft 18 is the hub 19, which has the radially extending webs 20. The outer edges of said radial webs are formed into a Y section 21, having inwardly turned lips 22, for receiving the screen sections 23, which have the hook-type edges 24, which fit over the lips 22. It will be noted that assembly of a number of the screen sections, with the hub and radially extending arms, form a multi-sided cylinder shown to be in this case, a chronically-shaped hexagon. 10

Mounted upon one end of the shaft 18 is the sprocket 40, which is fixed stationary thereto.

Supported on the upstanding members 25, which are mounted upon the cross-members 11, is the drive shaft 27, which is rotatably mounted 15 in the journals 41. Rigidly fixed on one end of the drive shaft 27, is the sprocket 38, which is rotatably fixed to the sprocket 40 on shaft 18, by means of the sprocket chain 29. Fixedly mounted on the other end of the shaft 27, is the bevel gear 42, which meshes with the bevel gear 37, fixedly mounted upon the jackshaft 36. Fixedly mounted upon the other end of the jackshaft 36, is the bevel gear 35, which in turn meshes with the bevel gear 34, which is rigidly 25 mounted on the shaft 32. Keyed to the shaft 32, is the undershot wheel 31, which operates in the fluid chute 30, through which the fluid is transmitted to the mud screen. The lower end of the shaft 18 is journaled in the bearing, which in turn 30 is supported by the member 15, hinged to the sub-frame structure by the hinge 16. The other end of this member 15, is arranged to rest upon the cam wheel 43, which is rigidly mounted on shaft 27. 35

In operation, the drilling fluid is transported to the mud screen through the chute 30, which it will be noted, extends into one side of the cylindrical portion of the mud screen. The energy in the moving fluid passing through and around the undershot wheel 31, transmits its energy of motion to said wheel. The radially extending webs 20 form an overshot water turbine wheel, to which the energy of the incoming fluid also transmits energy for rotating the screen cylinder. This 40 45 rotational motion transmitted to both the radially extending webs and the undershot wheel 31, are added through the bevel gears 34 and 35, the shaft 36, the bevel gears 37 and 42, the shaft 27, the sprockets 38 and 40, and the sprocket chain 29, to insure rotation of the screen, for the purpose of discharging the solids which are left inside the cylinder screen, after the fluid passes through the screen sections.

At the same time, the undershot wheel 31 tends 55

to govern the speed of rotation of the screen cylinder to that speed made possible through the beveled gear and sprocket wheel ratios, thus insuring the proper amount of screen surface for the screening of a proportionate amount of the liquid. There is a natural tendency for the solids which are left in the screen to cling to the screen surfaces. The cooperation by the lower member 15, upon which is journaled the lower 5 end of the shaft 18 and the cam wheel 43, transmits to the screen cylinder, a vibratory motion during the rotation of the shaft 21, which tends to dislodge any of the solid particles which might cling to the screen surfaces and in that way discharge the solid particles from the lower end of the screen cylinder.

The screen sections 23 are formed in a wedge shape, being narrower at one end than at the other. This construction allows the wedging of 20 these screen sections onto the radially extending webs 20, eliminating the necessity of other means of attachment, and allowing take-up, in case of the screen expansion during operations.

It is obvious that slight changes can be made 25 in the construction of the invention, without departing from the spirit of the invention, and with these in mind:

What I claim is:—

1. A shale separator comprising a support, an 30 inclined open ended rotatable screen having a radially webbed center and screen sections inter-fitted therewith to provide a multisided cylinder for receiving unfiltered material at the higher end thereof and discharging certain of the material 35 through the screen sections and the remainder of said material through the lowermost open end, rotatable means in the support carrying said cylinder, means for supplying unfiltered material to the screen above its axis of rotation through the higher end thereof, and means driven by 40

the energy of moving material in said last-named means and having connection with the first-named means for effecting rotation to said screen.

2. A shale separator comprising a support, an inclined open ended rotatable screen having a radially webbed center and screen sections inter-fitted therewith to provide a multisided cylinder for receiving unfiltered material at the higher end thereof and discharging certain of the material through the screen sections and the remainder of said material through the lowermost open end, rotatable means in the support carrying said cylinder, means for supplying unfiltered material to the screen above its axis of rotation through the higher end thereof, means driven by the energy of moving material in said last-named means and having connection with the first-named means for effecting rotation to said screen, and vibrators associated with the support and said first-named means and actuated by the last-named means.

3. A shale separator comprising a rotatable screen, means holding the screen in an inclined position, a rotatable power wheel for operation by the energy of moving matter being screened, 25 shaft and gear connections between the power wheel and the said screen for the transfer of power to the latter, hinged vertically swinging supports carried by the screen holding means and active upon the latter for vibration thereof, cams 30 operated by said shaft and gear connections for activity upon the hinged supports and imparting vibratory action thereto, the said screen being connected and arranged to discharge the most solid matter through its lowermost end, and means accommodating the power wheel and supplying liquid to the interior of the screen remote 35 from the discharge end thereof and at a point above and at one side of its axis.

JAMES H. CARSON.
